United States Patent Office

TURNER BARNES, OF GREENSBURG, INDIANA.

Letters Patent No. 69,387, dated October 1, 1867.

IMPROVEMENT IN HAND-SPINNING MACHINE.

The Schedule referred to in these Letters Patent and making part of the same.

TO WHOM IT MAY CONCERN:

Be it known that I, TURNER BARNES, of Greensburg, Decatur county, Indiana, have invented a new and useful Improvement in Hand-Spinning Machines; and I hereby declare the following to be a full, clear, and exact description thereof, reference being had to the accompanying drawings, making part of this specification.

My invention relates to the construction of a hand-spinning machine whose spindle is so mounted in an adjustable arm as to be capable of being swung back for drawing the yarn, and yet to preserve its proper angle and presentation with reference to the operator.

A is a bench mounted on the legs B B' B'', and having the customary post C, in which is journalled the shaft D of the main wheel or "rim" E, having the usual handle F, and also a crank, G, for a purpose hereafter explained. Hinged or pivoted to the end of the bench farther from the rim is a swinging arm or board, H, in whose free extremity is pivoted a vertical stem or head, I, which affords journal-bearing for the spindle J upon which the yarn is spun and drawn. A suitable whirl, K, in the spindle, carries a belt, L, which, passing over idlers M M', that are journalled to and vibrate with the head I, engages around a whirl, N, on the stem I, from whose sheave, O, another belt passes to a whirl, P, on a stem, Q, coincident with the pivot of the swinging arm, and from a sheave, R, on this whirl, another belt is carried around an idler, S, on a stem, T, to the rim or driver E. The pivoted end of the arm I takes the form of a scored sheave, V, around which are fastened two belts, W W', which are respectively connected to a weight or counterpoise, X, and a treadle, Y. The weight X acts to swing the arm I toward the operator, and the latter, when she desires to draw the yarn, presses her foot on the treadle, and at the same instant rotates the rim. In order that the spindle shall in every position be presented fair to the operator, I provide in the upper side of the arm a groove, Z, which guides a sliding-rod, 1, which, being connected by pitman 2 to a stem, I, and by another pitman, 3, to the under side of the bench A, the spindle is maintained at the same, or nearly the same angle or bearing, whether the arm I be advanced or retracted. It will be seen that in this arrangement the spindle is made to retain a horizontal or any other definite position and given bearing, while susceptible, also, of being alternately swung away from and toward the operator, for the operations of drawing, twisting, and winding. The stationary stem T may carry a flax-spinning spool and fliers, U. To adapt the machine for flax-spinning, the above-described belting is disconnected, and belts passed from the rim E to the spool and flier-whirls of the flax-spinner, and the treadle being disengaged from the rear leg B'', is connected by cord or pitman to the crank G, and its eye 4 is engaged over the hook 5 on the leg B'.

I claim herein as new, and of my invention—

1. The arrangement of spindle J, maintained in a given direction or bearing within the movable arm H by means of sliding-rod 1 and pitmen 2 3 and stem I.
2. In combination with elements of claim 1, I claim the arm H, adapted for being advanced and retracted by weight X and treadle Y, and their described or equivalent accessories, substantially as set forth.

In testimony of which invention I hereunto set my hand.

Witnesses:

GEO. H. DUNN,
WM. H. CARROLL.

TURNER BARNES.
